UNITED STATES PATENT OFFICE.

FRED J. KLEIN, OF NEW YORK, N. Y.

NOTE-BOOK HOLDER.

1,237,912.

Specification of Letters Patent. Patented Aug. 21, 1917.

Application filed September 22, 1914. Serial No. 863,053.

To all whom it may concern:

Be it known that I, FRED J. KLEIN, a citizen of the United States of America, and a resident of the borough of Bronx, in the city of New York, county of Bronx, and State of New York, have invented certain new and useful Improvements in Note-Book Holders, of which the following is a specification.

10 The object of this invention is to provide an inexpensive and convenient holder for stenographers' note books which will serve as a protection to a book when carried, afford a back to preserve an even surface when held in the lap and taking dictation, and will serve as a support for the book at a convenient angle beside the typewriting-machine when transcribing. A further object is to combine with the holder a suitable 15 page-marker.

In the accompanying sheet of drawings which forms a part of this application—

20 Figure 1 is a perspective view of a note-book-holder constructed in accordance with my invention and arranged to support the note book in position for reading when copying on a typewriting-machine.

Fig. 2 is a perspective of the holder broken away and without the note book.

25 Fig. 3 is an edge view showing the holder when closed over the book.

The holder comprises a pair of binders' boards, slightly larger in length and width than a standard stenographer's note book, 30 in which one serves as a back board 1 for the note book when taking notes and as a support when transcribing, and the other serves as a cover board 2 when the book is carried and as a prop for the first mentioned 35 board when set up beside a typewriting-machine for copying. The boards are hinged together through a connecting section 3 so that each board can fold to a right angle either way with the face of the connecting section. The board which supports the note book has riveted to it adjacent to the hinge a steel angle strip 4 with one side 40

projecting outwardly to form a rib against which the bound edge of the book abuts.

45 The angle strip is slightly longer than the width of the book and has a bent portion 5 at the left end through which one branch of a pointed bent wire 6 passes and lies in the angle of the angle strip. A tongue 7 cut from the angle strip is bent over this branch of the wire and holds it rigidly.

At the other end of the angle strip is a bent portion 8 through which pass both branches of a pointed bent wire 9 the point of which faces the point of the other wire and the two wires constitute facing points for engaging the leaves of the book adjacent to its binding. One branch of the pointed bent wire at the right also lies in the angle of the angle strip and is guided by a tongue 10 cut from the angle strip and folded loosely over this branch and permitting the point to be moved longitudinally over a space of about half of an inch.

A flexible flat leather strap 11 is pivotally 70 fastened at one end by an eyelet 12 to the face of the back board. At its other end the strip carries a clasp 13 which may be engaged either with a button 14 on the back board when laid flat along the edge of the 75 board, or may be engaged with either of a series of buttons 15 along the edge of the cover board to hold the two boards in angular relation by turning the strap on its eyelet pivot and folding it over the edges 80 of both boards. The amount of this angular relation or spread of the boards depends upon which button is clasped, and may be greater or less to suit the convenience of the user.

85 The connecting section carries a page marker 16 consisting of a bent wire one branch of which lies along this section guided by staples 17 and secured at its end which has a short bend by a staple 18. 90 From this branch at one end of the connecting section the wire is bent upward and back parallel to the face of the section to form a marker spaced from the section sufficiently for passing the leaves of the book 95 thereunder. The marker is set in a plane at right angles to the middle line of the section and in this position lies most naturally as a marker for about the middle leaves of the book when the covers are folded together with the book between, but the branch lying along the section is a torsion branch and permits the marker to deflect and lie without cramping between leaves at the front or back of the book when required.

100 In using the invention the movable point will be withdrawn as far as possible and the bound edge of the note book pressed into the angle of the angle strip and against the rib, and the book will then be in position to be 110 impaled on the facing points when the movable one is pushed in. When using a note

book with this holder the book will be written through, writing on one side of each leaf only. When taking dictation the leaves are thrown over the top of the marker as each page is filled and the marker is not shifted, then thrown back to the point of beginning shown by the marker and on transcribing each leaf is passed under the marker as the notes are copied therefrom. When the book has been written through, using one side of each leaf, and transcribed, it is then detached and reversed in the holder and the other sides of the leaves are used.

What I claim as new, and desire to secure by Letters Patent of the United States is—

1. A book-holder comprising a board, an angle strip attached to the board with one side of the strip facing outwardly from the board, and two facing points lying in the angle of the angle strip for engaging the leaves of the book adjacent to its binding, one of the points being longitudinally movable, substantially as described.

2. A book-holder comprising a pair of boards hinged together, means adjacent to the hinge for engaging the leaves of the book adjacent to its binding, a flexible strap pivoted at one end to the inside face of one

of the boards whereby it may be laid flat along that face of the board or turned and folded over the edges of both boards and secured at its other end to the face of the other board to hold the two boards in angular relation, and buttons on the faces of both boards for securing the free end of the strap, substantially as described.

3. A book holder comprising a pair of boards, a connecting section, hinges at opposite margins of the connecting section for connecting the boards, means adjacent to the connecting section for engaging the leaves of the book adjacent to its binding, and a marker consisting of a wire which is secured to the connecting section and carried opposite and parallel to the middle of the connecting section to form a marker spaced from the section sufficiently for conveniently passing the leaves of the book thereunder, substantially as described.

Signed by me at New York, in the borough of Bronx, New York this 21st day of September, 1914.

FRED J. KLEIN.
